PRINTING-TELEGRAPH SYSTEM.

1,095,541.

Specification of Letters Patent.

Patented May 5, 1914.

Application filed May 11, 1911. Serial No. 626,427.

To all whom it may concern:

Be it known that I, CHARLES G. ASHLEY, a citizen of the United States of America, and a resident of Chicago, county of Cook, and 5 State of Illinois, have invented a new and useful Improvement in Printing-Telegraph Systems, of which the following is a specification.

My invention pertains to automatic printing telegraph systems of the class employing a plurality of component printing elements or types, the complete legible characters being formed of impressions in proper relation and sequence from a plurality of the component types representing the various component parts of the characters to be recorded.

In an application filed by me on February 6th, 1911, Serial No. 606734, I have disclosed a system of printing telegraphy in which a 10 plurality of printing elements are electromagnetically operated over one of a pair of line conductors and ground to make contact with a record sheet, while the recording of an impression of any element of the group 15 is selectively controlled over the remaining line conductor and ground. Thus current impulses of variant polarity over one line conductor and ground operate the printing elements to make contact in predetermined 20 groups with a record sheet, while current impulses of variant polarity over the other line conductor and ground cause the selective imprinting of any printing element of a group in contact with the recording sheet.

It is with a view toward simplifying the system and decreasing the installation cost that my present invention is directed. I accomplish this and other desirable features which will be subsequently herein disclosed 25 by a novel arrangement of apparatus and circuits which enables me to transmit intelligence and record the same in the Roman alphabet by the use of but a single line conductor.

In the figures which accompany and form a part of this specification and in which like numerals designate corresponding parts throughout, Figure 1 illustrates in diagram the apparatus and circuits at both a transmitting and receiving station, together with the line conductor connecting them. Fig. 2 is a plan view of the under side of one portion of the receiving apparatus of my improved system. Fig. 3 is a magnified view 30 of the monogram or the impressions of the

printing type elements as they would appear were all of the types imprinted on a stationary recording surface. Fig. 4 shows a section of transmitting tape perforated with all the combinations of perforations necessary to transmit all of the characters of the Roman alphabet, and the numerals from 0 to 9. Fig. 5 shows graphically the periodicity of the voltage of the current used to effect the selection of the imprints of the type faces and is so placed with relation to Fig. 4 as to clearly disclose the time relation existing between the magnet selection currents and the imprint selection currents. Fig. 6 illustrates a sectional transmitting 40 tape perforated to form all of the characters necessary to transmit intelligence in the Roman alphabet with my improved system, and also shows the character and outline of the letters and numerals as recorded by my improved receiving device.

Referring to Figs. 1 and 2, the receiving device of my improved system is shown in diagram at the left of Fig. 1 and comprises a permanent polarizing magnet 9 of substantially rectangular form, within which is mounted an electromagnet 10, presenting a pole face, substantially midway between the poles of the polarizing magnet 9. An armature 12 is placed opposite the free pole of electromagnet 10 and between the poles of the polarizing magnet 9. This armature is pivoted at its central portion between two non-magnetic journal plates 13 and 14 by means of the trunnion screws 5 and 6. 45 Strips of ivory or other insulating material, 12¹ and 12² are rigidly attached to the under portion of the armature 12, near its outer extremities. These insulating strips normally rest lightly against four light non-magnetic springs 1, 2, 3, and 4, which are rigidly attached at one extremity to the polarizing magnet 9 and are insulated therefrom and from each other by means of the insulating blocks 7 and 8. Each spring 50 bears on its free extremity an iron printing element or type face 1¹ 2¹ 3¹ and 4¹. The springs with their respective type face will be hereafter referred to as printing pens. The springs bearing elements 1¹ and 2¹ are 55 connected together as are the springs bearing elements 3¹ and 4¹. A platinum surfaced anvil 11 is placed opposite the printing elements 1¹, 2¹, 3¹ and 4¹ and is adjustable in its distance therefrom by means of 60

55 65 70 75 80 85 90 95 100 105 110

the screw as indicated. A tape sensitized with any of the well known chemical compounds for electrolytic printing, such as a mixture of nitrate of ammonium, chlorid of ammonium and red prussiate of potassium, rests on the surface of the anvil in a position to receive impressions from any one of the printing type faces. The printing pens 1, 2, 3 and 4 are normally held out of contact with the receiving tape 11¹ through their inherent spring tension, which causes them normally to assume a relaxed position and bear lightly against the insulating strips 12¹ and 12² of armature 12, thus tending to aid the polarizing magnet 9 to maintain armature 12 normally in a substantially horizontal position when magnet 10 is deenergized.

An electromagnetically polarized relay 100 comprising the operating electromagnets 15 and 16, polarizing electromagnet 18, armature 17 and contacts 25 and 26, has the windings of its operating magnets 15 and 16 so placed with relation to each other that a current impulse through the windings in series induces unlike poles on the opposed or operating extremities of the cores, while a current impulse through the windings in a direction opposite from that of the first impulse reverses the respective polarity of the pole faces. The windings of electromagnets 15 and 16 and the winding of electromagnet 10 are connected in series between the line conductor 29 and ground 28. A pair of batteries 21 and 22, or equivalent sources of current, have their terminals of opposite polarity connected together and through an adjustable resistance 20 with one terminal of the polarizing magnet 18 of relay 100, the other extremity of which is connected to armature 17; and also through 20 and 18 and a resistance 19 and conductor 24 with one of the blades of a double pole, double throw knife switch 42, the other blade of which is connected through conductor 23 with the conductor joining the opposite terminals of batteries 21 and 22. One terminal of a pair of terminals of knife switch 42 is connected to the conductor joining printing pens 3 and 4, while the other terminal of the pair is connected to the conductor joining printing pens 1 and 2. The pairs of printing pens 1, 2 and 3, 4 are connected to the second pair of terminals of knife switch 42 in reverse order from their connection to the first pair of terminals by means of the crossed jumper wires on the switch 42 as indicated.

Referring now especially to relay 100, it will be observed that if the armature 17 is in contact with contact 25 current will flow from battery 21 through contact 25, armature 17 and thence through the helix of electromagnet 18 to the negative pole of battery 21, to induce a N. pole upon the free

extremity of armature 17, while if armature 17 is in contact with contact 26 current will flow from battery 22 through the helix of electromagnet 18, armature 17, contact 26 and thence to the negative pole of battery 22, to induce a S. pole on the free extremity of armature 17. Assume now that armature 17 is at rest in contact with contact 25 and that an alternating current of a definite periodicity is traversing the helices of magnet 15 and 16 to ground 28, the positive waves of the current will induce a S. pole on the pole face of magnet 16 and a N. pole on the pole face of magnet 15, while the negative waves of current will induce a S. pole on the pole face of magnet 15 and a N. pole on the pole face of magnet 16; thus, as armature 17 is in contact with contact 25 and is presenting a N. pole to the pole face of electromagnet 15 and as a positive impulse of current through the helices of magnets 15 and 16 produces a N. pole on magnet 15 and a S. pole on magnet 16, armature 17 is attracted by magnet 16 to break contact with contact 25 and make contact with contact 26 which changes the direction of current through the helix of magnet 18 and thereby produces a S. pole on the extremity of armature 17. A negative impulse of current following the previous positive impulse through the helices of magnets 15 and 16, induces a N. pole on magnet 16, thereby tending to hold armature 17 in contact with contact 26, while a positive impulse of current following the previous negative impulse, induces a S. pole on magnet 16 and a N. pole on magnet 15, thereby attracting armature 17 to break connection from contact 26 and make connection with contact 25, which changes the polarity of its free extremity from S. back to N. and it is held in contact with contact 25 until the next succeeding positive impulse through the helices of magnets 15 and 16. It is therefore obvious that a current of a definite periodicity through the helices of magnets 15 and 16 will produce in the helix of magnet 18 a current which is in effect an alternating current of one half the periodicity of the operating current and that this current of one-half periodicity is impressed on the printing elements in pairs in shunt with the winding of magnet 18.

Referring now to the transmitter which is shown in diagram at the right of Fig. 1, an alternating generator 38 is belted to any convenient source of power and is geared through shaft 35 and spur gears 37 and 36 with a conducting drum 33 which is rotatively mounted between journals by means of the shaft 34. A brush 30 may bear upon and make contact with the surface of the drum 33 and is connected to the line conductor 29. One terminal of the generator 38 is grounded at 39, while the other termi-

nal is connected to both the journal of drum 33 and through an adjustable resistance 31 to line conductor 29. This allows of placing on the line 29 through the ground two intensities of current, one through the drum 33 and brush 30 and the other through the adjustable resistance 31; the latter current value being adjustable through a wide range of intensity by means of the adjustable resistance 31. Assuming now the brush 30 to be out of contact with the drum 33 and the generator 38 in operation, an alternating current may be placed through the adjustable resistance 31 on the line 29 through the helices of electromagnets 10, 15 and 16 to ground 28, of such a value that relay 100 may be adjusted through the adjustable resistance 20 to be responsive thereto while the armature 12 opposite magnet 10 is unresponsive. This results in placing a potential alternating at one-half the periodicity of the line current on the pen faces 1¹, 2² 3³ and 4⁴ without moving the pen faces.

25 The drum 33 is provided with a median row of equally spaced insulating invaginating projections 33¹ which are so spaced with relation to the ratio of speed of the drum 33 and generator 38, that while the drum 33 is rotated through an angular distance defined by that between any two projections 33¹ the generator 38 is placing on the drum 33, four positive potentials and four negative potentials and placing upon the line 35 four complete current cycles. Thus, if a transmitting tape 32 is provided with a median row of registry perforations and is placed on the drum 33 so that its registry perforations engage the projections 33¹, it 40 will be possible by correctly spacing a perforation in the tape in relation to its longitudinal distance, from any registry perforations, to send either a positive or a negative impulse from generator 38 through drum 45 33 and brush 30 to line conductor 29. This impulse will be in phase with the current placed on the line through adjustable resistance 31 and, as the impulse is placed on the line through a shunt of comparatively 50 low resistance compared to the resistance 31, it will be of augmented energy as compared with the impulses sent through resistance 31 to operate the polarized relay 100, and will thus energize magnet 10 to attract 55 either end of armature 12, depending upon the polarity of the impulse. Armature 12 may thus be operated selectively to depress pen faces 1¹, 3³, or 2², 4⁴ simultaneously into contact with the receiving tape 11¹ and as 60 relay 100 by its operation, as hitherto explained, places a potential on the pen faces which reverse in direction twice while the line current potential reverses four times, it follows that both pairs of pens 1¹, 3³ and 65 2², 4⁴ may be successively brought into con-

tact with tape line 11¹, while the potential impression on their faces is either positive or negative.

If the anvil 11 be platinum coated and the tape 11¹ be impregnated with the chemical compound previously mentioned, it is obvious that either pen faces of a pair in contact with the recording tape 11¹, may be imprinted thereon depending upon which pen face of a pair is at a positive potential with respect to the tape 11¹. Thus, assuming armature 17 of relay 100 to be maintained in operation by an alternating current from generator 38, through resistance 31 to line conductor 29, if a positive impulse of current be sent through the brush 30 to line conductor 29 it will operate armature 12 to depress pen faces 1¹ and 3³ simultaneously into contact with tape 11¹ and pen 1¹ or 3³ will be at a positive potential with respect to tape 11¹ depending upon whether armature 17 is at that instant in contact with contact 25 or 26 respectively. Similarly, a negative impulse of current sent through brush 30 over line conductor 29 will cause armature 12 to depress pen faces 2² and 4⁴ simultaneously into contact with tape 11¹ and either pen 2² or 4⁴ will be imprinted thereon dependent upon whether armature 17 is in contact with contact 25 or 26 respectively.

In Fig. 3 I have shown an enlarged view of the pen faces as they would appear were all of the types imprinted on a stationary recording surface, or it may be considered a plan view of the printing faces or elements in their position in the receiver. Plans 1¹, 2² and 3³ are in width each equal to the width of a complete normal character such as H. The width of a complete normal character is divided into eight arbitrary units, each pen face being separated from its fellow by one of these arbitrary units.

Referring now to Figs. 4 and 5, the phase relation that must exist between the line current and the current impressed on the pen faces, in order to imprint legible characters with an arrangement of perforations as shown in Fig. 4, is clearly indicated. Pen 110 face 4⁴ is imprinted by sending a negative impulse from generator 38 through brush 30 over line 29 through magnets 10, 16 and 15 to ground which causes armature 12 to depress pens 2 and 4 simultaneously into contact with tape 11¹ and assuming that armature 17 of relay 100 is at that instant in contact with contact 26, current will flow from battery 22, through conductor 23, lower blade of knife switch 42, conductor joining 115 pens 3 and 4, spring of pen 4, pen face 4⁴, tape 11¹, pen face 2², spring of pen 2, conductor joining pens 2 and 1, upper blade of knife switch 42, conductor 24, resistance 19, armature 17, contact 26 to battery 22, there- 120 125 130

by causing pen face 4⁴ to assume a positive potential with respect to tape 11¹ and causing thus its imprint thereon but not causing the imprint of pen face 2². Pen face 2² is imprinted by sending from generator 38 through brush 30, line 29, helices of magnets 10, 16 and 15 to ground, a negative impulse following the positive impulse immediately succeeding the negative impulse which caused the imprint of pen face 4⁴. As has hitherto been explained the positive impulse succeeding the previous negative impulse, has caused armature 17 to break connection from contact 26 and make connection with contact 25. Thus, as the negative impulse under discussion has caused armature 12 to again depress pen faces 2² and 4⁴ simultaneously into contact with tape 11¹, current flows from battery 21 through contact 25, armature 17, resistance 19, conductor 24, upper blade of knife switch 42, conductor joining pens 1 and 2, spring of pen 2, pen face 2², tape 11¹, pen face 4⁴, spring of pen 4, conductor joining pens 4 and 3, lower blade of knife switch 42, conductor 23 to battery 21, thus causing pen face 2² to become positive with respect to the tape 11¹ and thereby causing its imprint thereon, but not causing the imprint of pen face 4⁴. Similarly two positive impulses separated by a negative impulse selectively cause the imprinting of pen faces 3³ and 1¹.

Fig. 4 illustrates the relation between the operating perforations and the registry perforations and shows the relation existing between the registry perforations and all of the perforations necessary to operate the printing pens in such sequence as to form legible characters. The longitudinal line 30¹ is an arbitrarily chosen contact line between the brush 30 and the drum 33 along which the pen-selective perforations are spaced. The longitudinal line 33² is a median line along which the registry perforations are spaced. The transverse lines 4⁰, 3⁰, 2⁰, and 1⁰ are placed a distance apart equal to, or proportional to the unit of width of the pen faces 1¹, 2², and 3³ dependent upon the ratio of the speed of the transmitting and receiving tapes. For the purpose of clearness in this disclosure I will assume that this tape interval is equal to the unit of width of the pen faces, 1¹, 2² and 3³ as illustrated and that the transmitting and receiving tapes move through commensurate distances in equal times. Thus, in order to selectively imprint any pen face it is only necessary to place a perforation along the line 30¹ opposite a registry perforation, or one, two or three tape intervals removed therefrom, dependent upon the pen face which it is desired to imprint.

The manner of forming legible characters by the use of a tape perforated in accordance with that illustrated in Fig. 6, is as

follows: Assuming that generator 38 is placing an alternating current on line 29, through resistance 31, which is operating armature 17, at one-half the frequency of the line current; that tape 32 perforated as shown in Fig. 6 is in such a position on drum 33 that its registry perforations engage the projections 33' and that the tape is being drawn under brush 30 by means of the train of gears 36 and 37 at a speed which is proportional to the generator speed as hitherto indicated, then a perforation along the line 4⁰ places through the brush 30 to line 29 an augmented negative impulse which imprints pen face 4⁴ as previously disclosed and after a time interval of eight tape units a perforation along another line as 4⁰ allows another augmented negative impulse to flow through brush 30 to line 29 again imprinting pen face 4⁴ which, as the receiving tape 11¹ is considered to be moving through a commensurate distance from right to left under pen face as indicated in Fig. 3, while the transmitting tape 32 is moving eight tape intervals, imprints the second imprint of pen face 4⁴ upon the receiving tape a distance away from the previous imprint of eight receiving tape units, or the width of a complete normal character. After the tape 32 has passed under the brush 30 a distance of two more tape intervals, a perforation along the line 2⁰ allows an augmented negative impulse to flow through brush 30 to line 29, which, as before noted, follows an unintensified positive impulse through relay 100 which has changed the direction of current through the pen faces when in contact with the receiving tape 11¹ and therefore the negative impulse under discussion results in imprinting pen face 2². As the two previous imprints of pen face 4⁴ have before the imprinting of pen face 2² moved under the type faces as viewed in Fig. 3, a distance of two units of width of a complete normal character, pen face 2² is imprinted with its extremities abutting the two previous imprints of pen face 4⁴. After tape 32 has passed under brush 30 one more tape interval a perforation along the line 1⁰ allows of an augmented positive impulse being sent through the brush 30 over line 29 which imprints pen face 1¹ and as the tape 11¹ carrying the imprints of pen faces 4⁴ and 2² has in the interim moved one unit of width of a normal character to the left under the pen faces as viewed in Fig. 3 type face 1¹ is imprinted in such relation to the previous imprints that its vertical leg registers with the upper half of the first imprint of pen face 4⁴, while the extremity of its horizontal leg abuts the latter imprint of pen face 4⁴ to form the character A. In a similar manner all of the characters necessary to transmit intelligence in any language using the Roman alphabet may be transmitted and imprinted.

It will be observed from the foregoing and from a study of Figs. 4 and 5 that a definite phase relation must at all times be maintained between the line current and the current impressed on the pen faces through the operation of armature 17 of relay 100 in order to transmit intelligence with the design of apparatus and circuits used and with the predetermined arrangement of perforations in the tape with respect to the registry perforations. This phase relation depends entirely upon the initial or starting position of armature 17 with respect to its contacts and can be maintained by manually setting the armature 17 during its periods of rest in contact with the proper contact so that when generator 38 is started the phase relation of the line current and printing current will always be in proper relation to each other to insure the imprinting of the proper pen face for a predetermined spacing of the perforations with relation to their registry perforations. This necessity for manually re-setting the armature 17 is obviated by providing the double pole reversing switch 42 with which the operator may reverse the current through the pairs of pen faces in contact with the tape 11'. Thus, if a test tape perforated with a series of perforations along the line 40', each spaced opposite a registry perforation to imprint a series of imprints from the pen face 4⁴ be preliminarily sent through transmitter before a message tape, the receiving operator may by observing the resultant record, note whether the printing currents are in contact phase with the line currents, by observing whether a series of equally spaced vertical lines are printed or whether the opposite pen of the pair, as 2², is producing a series of short lines resulting in a record having the form of a continuous median line. If median line be received the operator reverses the position of the reversing switch 42 and a series of imprints from the pen face 4⁴ results upon the receiving tape, signifying to the operator that the apparatus is in a condition for receiving a message.

While I have illustrated and described only one embodiment of my device, it is to be clearly understood that I may make numerous changes therein without departing from the spirit or narrowing the scope of my invention.

Having thus described my invention what I claim as new and desire to secure by United States Letters Patent, is as follows:

1. In a printing telegraph system, a plurality of printing elements a printing surface, means responsive to current impulses of variant polarities and predetermined intensity to effect the selective operation into contact with said printing surface of predetermined groups of said printing elements, and means responsive to current im-

pulses of a predetermined polarity to effect the selective imprinting of any element of an operated group of said elements.

2. In a printing telegraph system, a printing surface, a relay responsive to a continuous series of impulses of alternating polarity and normal and maximum current intensity, and a plurality of printing elements operable selectively in predetermined groups into contact with said printing surface of all the elements of a group by means of current impulses of variant polarities and of said maximum current intensity, said relay by its operation effecting the selective imprinting of any element of a group of said elements. 70

3. In a printing telegraph system a printing surface, a plurality of printing elements, an operating electromagnet responsive to current impulses of variant polarities and predetermined intensity to effect the engagement of said printing surface with said elements in predetermined groups, and a relay responsive to current impulses of predetermined polarity and lower intensity to effect 80 the selective imprinting of any element of an operated group of said elements. 85

4. In a printing telegraph system, a plurality of printing elements, a record sheet, an operating electromagnet for said printing elements responsive to current impulses of variant polarity and predetermined intensity to effect the selective operation of said elements in predetermined groups to make contact with said record sheet, and a 90 relay responsive to current impulses of predetermined polarity and variant intensity, to effect the selective imprinting of any element of a group of said elements in contact with said record sheet. 95

5. In a printing telegraph system, a relay responsive to continuous series of impulses of predetermined polarity and normal and amplified current intensity, a plurality of printing elements, a record sheet therefor, 100 said printing elements being operable selectively in predetermined groups by means of current impulses of variant polarity and amplified intensity to make contact with said record sheet, said relay by its operation 110 effecting the selective imprinting on said record sheet of any element of a group of said elements in contact therewith. 115

6. In a system of printing telegraphy, a printing surface, an electro-magnetically 120 polarized relay operated by current impulses of predetermined polarity, a plurality of printing elements operable selectively in predetermined groups by current impulses of variant polarities and of augmented intensity to the impulses operating said relay, said relay by its operation effecting the selective imprinting of any element of a group of said elements operated into contact 125 with said printing surface. 130

7. In a printing telegraph system, a plurality of printing elements, a relay, said relay being operable to place upon said printing elements current impulses of variant polarity and of a predetermined frequency, said printing elements being operable selectively in predetermined groups by means of current impulses of variant polarity and of augmented intensity to the currents operating said relay.

8. In a printing telegraph system, a receiving station, a transmitting station and a line conductor and ground connecting them, means at said transmitting station for impressing upon said conductor and ground an alternating current of a definite frequency and variant intensity; a relay at said receiving station operated by said alternating current, a printing surface, a plurality of printing elements, means for utilizing one value of the intensity of said alternating current to effect the selection of a group of said printing elements, and for moving them into engagement with said printing surface, and means for utilizing the operation of said relay to effect the selective imprinting of any one of an operated group of said elements.

9. In a printing telegraph system, a transmitter, a receiver and a line connecting them, said transmitter being operable to place on said line an alternating current having normal and amplified current values; a plurality of printing elements, an operating magnet therefor, and a relay operable by impulses of said alternating current of a predetermined polarity and normal current value to impress on said printing elements, current impulses of one-half the frequency of said operating alternating current, said printing elements being operable selectively in predetermined groups through said operating magnet by means of impulses of said alternating current of variant polarity and of said amplified current value.

10. In a printing telegraph system, a receiving station, a transmitting station and a line conductor and ground connecting them, means at said transmitting station for impressing upon said conductor and ground,

an alternating current of a definite frequency, and intensity, and current impulses of variant polarity and augmented intensity in phase with said alternating current; a relay at said receiving station, operated by said alternating current, a plurality of printing elements, means for utilizing said current impulses of variant polarities and augmented intensity to effect the selection of a predetermined group of said printing elements, means for utilizing the operation of said relay to effect the imprinting on a receiving surface of any of said elements of said selected group.

11. In a printing telegraph system, the combination with a sending station, a receiving station, and a connecting line consisting of one wire and ground, of two groups of printing characters and a receiving surface at the receiving station, a source of alternating current, and means controlled from the sending station for primarily selecting a group of characters and moving same into contact with the receiving surface, and secondarily selecting a desired character from the selected group by impulses flowing over said connecting line.

12. A source of alternating current, a second alternating current controlled by the first so that it will have one-half the frequency of the first, a series of four printing characters, and means controlled by the joint action of the two currents for printing said characters selectively.

13. The combination with four printing characters, of means for producing two alternating currents, means operating through one current for controlling the other so that the frequencies of the two currents will be to each other as two to one, and means operating through the conjoint action of the two currents for printing said type selectively.

Signed by me at Toronto, county of York, and Province of Ontario, in the presence of two witnesses.

CHARLES G. ASHLEY.
